UNITED STATES PATENT OFFICE

CHARLES THOMAS HOFFMAN, OF WASHINGTON, DISTRICT OF COLUMBIA, ASSIGNOR OF
ONE-HALF TO EMORY L. GROFF, OF WASHINGTON, DISTRICT OF COLUMBIA

MEANS FOR AUTOMATICALLY DEFROSTING REFRIGERATING UNITS

Application filed July 3, 1929. Serial No. 275,847.

This invention relates to refrigeration, and more particularly to a novel and practical means for automatically defrosting the refrigerating unit at predetermined intervals.

5 It is well known that the refrigerating units or cooling coils of automatic electrical refrigerators of the type now generally in household use, become coated with frost or ice which must be permitted to melt away at 10 intervals to preserve the efficiency of the box. According to the present practice it is customary to manually cut off the current supply to the motor of the refrigerating apparatus and temporarily allow the box to 15 stand until the frost or ice melts from the refrigerating unit whereupon it is necessary manually to restore the circuit to the motor and compressor to again start the freezing cycle. The defrosting of refrigerators is 20 more or less of a nuisance especially in household refrigerators where the user has the impression that all of the functions and operations of the machine are automatic. Some users might be disposed to promptly and 25 periodically defrost while others might allow too much frost or ice to form and consequently not only reduce the efficiency of the box but perhaps cause other damage and inconvenience.

30 Accordingly, the present invention contemplates simple, practical and reliable means for temporarily breaking the circuit to the motor of the refrigerating apparatus until the ice or so-called frost has melted away 35 whereupon the circuit will be automatically restored and the box again put in operation without requiring manual attention.

A primary object of the invention is to provide a device including a novel circuit and 40 circuit controlling means which is operated by direct contact or engagement with the frost or ice forming on the fins or other part of the refrigerating unit.

Another object of the invention is to provide means for visually indicating occurrence 45 of the defrosting operation.

A further object of the invention is to provide a construction which will be safe and in every way meet underwriters' requirements both as to the type of switches involved

and the means for closing the circuit so that no arcing or sparking will occur during the operation of the device. Also, in that connection the invention contemplates the use of electrical devices in which no current is allowed to flow except for an instant at the beginning and end of the defrosting cycle. 55

A still further object of the invention is to provide means for controlling or setting the circuit closing means in such a way that 60 more or less ice or frost may be permitted to form before the circuit is closed thereby enabling the user to time the defrosting cycle accurately so that he will not only know how often the defrosting operation will occur but in the event that it should occur at 65 an undesirable time the cycle can be changed easily and without difficulty so as to delay defrosting at a particular time, thereby giving the user complete control of the defrost- 70 ing cycle in a simple and practical manner.

With the above and other objects in view the invention consists in the novel features of construction, combination and arrangement of parts as will be hereinafter more 75 fully described, illustrated in the accompanying drawings and defined in the appended claims.

A preferred and practical embodiment of the invention is shown in the accompanying drawings, in which:

Figure 1 is a diagrammatic view illustrating the circuit arrangement and the mechanical devices operated in conjunction therewith, the parts being shown in position about to start the defrosting cycle. 85

Figure 2 is a view similar to Figure 1 showing the position of parts during the defrosting cycle and with the circuit controller of the device about to restore the refrigerating circuit. 90

Figure 3a is a detail vertical sectional view of the circuit controller.

Figure 3 is a detail view of the circuit controller which contacts with the ice. 95

Figure 4 is a detail sectional view taken on the line 4-4 of Fig. 1.

Figure 5 is a detail view of the terminal changing switch.

Figure 6 is a diagrammatic view illustrat- 100

ing a modified arrangement of the construction shown in Figs. 1 and 2.

Figure 7 is a detail view of the universal mounting for the device which controls the defrosting circuit.

Similar reference characters designate corresponding parts throughout the several figures of the drawings.

In carrying the invention into effect it is proposed to provide a simple and compact arrangement that will reliably function under all conditions and use, and which will be controlled directly by the frost or ice forming on the fins or elsewhere and by box temperature at the end of the defrosting cycle. That is to say, when ice builds up to a certain height or depth on the cooling unit, the circuit will become automatically closed to cut off the supply of current to the motor of the refrigerating apparatus, and as soon as the ice melts and the temperature of the box rises, the circuit will be automatically restored.

Referring to the drawings, the present invention comprises in its organization a defrosting control unit including a circuit controller or switch A adapted to directly contact with the ice, the same being mounted on an arm B pivotally supported on a shaft or axis C which also carries a base D on which other elements of the unit are mounted so that when the position of the arm B is adjusted through the means of the device E to bring the circuit closer or switch A a greater or less distance from the cooling coil or fin, all the operating parts of the device may be likewise adjusted to insure the proper functioning of the arm B. It will, of course, be understood that the purpose of adjusting the circuit controller A is to control the timing of the defrosting cycle, that is to say, the timing of the defrosting cycle can be shortened or lengthened according to the depth of the ice formation on the cooling unit by setting the circuit controller A at a greater or less distance from the part on which the ice forms.

The circuit controller A is intended and adapted to control what may be termed a defrosting circuit as distinguished from the refrigerating circuit which includes the line wires *x* and *y* leading to the motor of the usual refrigerating apparatus, and the wire *y* having therein a master switch S which is opened and closed by an actuator element designated generally as F. This element is preferably pivoted on the axis or shaft C and has connected to one end thereof a spring G whose opposite end is connected to a switch lever H pivoted to the arm B as indicated at I and carrying therewith a contact member K adapted to alternately engage with contacts L and L' to close the circuit to an electro-magnet M, first for an instant at the beginning of the defrosting cy-

cle and then again for an instant at the end of the defrosting cycle so that no current is flowing through any part of the apparatus except for a short time at the periods referred to. The electromagnet M operates in conjunction with an armature element designated generally as N which in turn alternately operates first one and then the other of a pair of dogs O and O' which are adapted to engage the actuator lever F on opposite sides of its center at alternate reciprocations of the armature member N thereby to snap the actuator F from the position shown in Figure 1, for example, to the position shown in Figure 2 and back again according to the conditions controlled by the circuit controller A.

With the parts shown in the position in Figure 1, the switch S of the refrigerating circuit is closed, but the instant that the ice formation comes into sufficient proximity or touches the casing of the circuit controller A, the control circuit will be operated to cause the actuator F to pull away from the terminals of the switch S of the refrigerating circuit and break the circuit. The arm B will then be pulled toward the ice formation on the cooling coil with a relatively light pressure so that as the ice melts, the circuit controller A will follow the same until it reaches the fin of the cooling unit or of the casing, which ever it might be.

While the actuating arm F is in defrosting position, that is with the switch S open, it closes an indicator circuit R to visually show that the refrigerator is defrosting.

When the ice melts away from the cooling coil and the temperature of the box rises, the circuit controller A will again come into operation to close the circuit to the electromagnet M and thus cause the operation of the armature N and pull the dog O (Figure 2) so that it will move the actuator F sufficiently past dead center to permit the spring G to move the arm upwardly and reset the same for the next refrigerating cycle while simultaneously restoring the refrigerating circuit through the closing of the switch S.

Referring more specifically to the details of construction, which, of course, may be varied within the scope of the invention, reference will first be made to the circuit controller.

This device is preferably of the spring thermostat thermometer type and includes a suitable casing 1 having the front wall 1a which contacts with the ice made of metal. This wall carries therewith a stud 1b on its inner face on which the arm or pointer 2 and its shaft 3 are rotatably mounted. The shaft 3 preferably consists of a metallic portion 3a which fits over the stud 1b and an insulated portion 3b which is secured to the end of the shaft 3 by means of a fastening 3c. The thermostat spring 4 has one end an-

chored to the metallic plate 1a and the opposite end anchored to the shaft 3 and said spring is intentionally mounted on the plate 1a so that cold may be better conducted to

5 the spring 4 to render the action of the coil and the arm 2 more positive when the ice strikes or extends into close proximity to the plate 1a. The arm 2 which is moved by the thermostat member 4 is adapted to co-
10 operate with contacts 5 and 6 carried by the casing 1 but insulated therefrom in any suitable manner. These contacts are preferably adjustable, that is they may be placed closer together or farther apart on the line
15 15 of the arc described by the end of the arm 2. The contact 5, for example, is intended to be engaged by the arm 2 when the ice formation on the cooling unit U extends into close proximity to or touches the member 1a of the cas-
20 ing 1, and on the other hand when the ice melts away, and the temperature of the box rises, the thermostat coil 4 will move the arm 2 into engagement with the contact 6.

The contact 5 is connected by a wire 5a
25 with the terminal L of the terminal chang-
ing switch which includes the lever H, and
the contact 6 is connected by the wire or other
conductor 6a with the terminal L' of said
switch. The contact member K of the ter-
30 minal changing switch H is electrically con-
nected by the wire 9 with one terminal of a
dry rectifier 10. This rectifier may be of any
standard type now available on the market
such as a Kodel or Elkon rectifier whose ter-
35 minals are connected with a step-down trans-
former 11 which is in turn connected to a
source of 110 volt A. C. supply. The pur-
pose of this transformer and rectifier is to
furnish a low voltage direct current, when
40 temporarily required, to the electro-magnet
M and to that end the said electro-magnet is
included in circuit with the rectifier by the
wire 12. The said electro-magnet is also con-
nected by the wire or other conductor 13 di-
45 rectly with the arm 2 of the circuit controller
A. Therefore, as the arm 2 moves from one
side to the other, under changing tempera-
ture conditions, the circuit will be automati-
cally and temporarily closed through the
50 electro-magnet M according to which one
of the contacts L and L' is engaged by the
contact member K.

To prevent any arcing or sparking inci-
55 dent to the making and breaking of the cir-
cuit in the terminal changing switch H a
condenser 14 may be connected across the
lines 9 and 13. Any tendency to produce a
spark in the switch H will, therefore, be ab-
sorbed by the condenser action.

60 Each time the electro-magnet M is ener-
gized, that is at the beginning and at the end
of the defrosting cycle, due to the closing
of the circuit first by the arm 2 engaging
with the contact 5 and then by the arm 2
65 engaging with the contact 6, the armature ele-

ment N will be moved or lifted. This arma-
ture member is preferably slidably guided in
a bracket 15 mounted on the base D and is
maintained in its normal position, that is,
away from the electro-magnet M by a spring 70
16 confined between the bracket 15 and the
head 17 which is adapted to engage alter-
nately with the dogs O and O'.

As previously indicated the said dogs O
and O' are carried by the arm B in any con-
venient and suitable manner. For example,
the said dogs have their shank portions 18
mounted in suitable guides 19 so that their
shanks will not turn, said guides being car-
ried by the arm B and provided with the 75
abutments 20 against which the springs 21 act
to maintain the dogs in their normal posi-
tion. The lower ends of the dogs may be
provided with the angular or equivalent por-
tions having the offset fingers 23 for engag- 80
ing with the actuator lever F.

With the arrangement of the dogs O and
O' shown in the drawings, it will be appar-
ent that the hooked ends 24 thereof are
adapted to be alternately moved or swung 85
into the path of movement of the head 17 of
the armature element N. That is to say, as
shown in Figure 1, when the circuit con-
troller A is about to close the circuit by en-
gaging with the contact 5, the dog O' will 90
have its hooked portion 24 in position to be
engaged by the head 17 of the armature
member. When the defrosting circuit, which
includes the circuit controller A and the ter-
minal changing switch H is closed the arma- 95
ture element N will be pulled toward the
electro magnet M, thereby pulling the dog
O' with it so that the finger 23 of the dog
will move the actuator lever F against the
tension of its spring G until the lever is moved 100
past center and the spring G will snap the
actuator lever F to the position shown in Fig-
ure 2, thereby breaking the circuit between
K and L but leaving the arm B under ten- 105
sion of the spring G so that the circuit con-
troller A will follow the ice formation to-
ward the cooling unit. 110

It will of course be apparent that when
the dog O' moves the actuator F, the refrig- 115
erating circuit will be broken by the open-
ing of the master switch S, due to the fact
that the conductor element 25 on the actua-
tor F will leave the terminals of the master
switch and thus open or break the refrigerat- 120
ing circuit.

When the box temperature rises due to the
melting of the ice the arm 2 will move to-
ward the contact 6 of the circuit controller
A. When the arm 2 closes the circuit through
said contact 6, the defrosting circuit is then 125
again closed with the parts in the position
shown in Figure 2, whereupon the dog O will
be moved by the armature element N thereby
to cause said dog to move the actuator F back
to the position of Figure 1 whereupon the 130

arm B will be set to its original position and also the actuator F will close the master switch S and restore the refrigerating circuit.

5 As previously explained, when the apparatus is in defrosting position, an indicating circuit R will be closed due to the fact that the contact strip 26 on the actuator F bridges the terminals of the indicator switch

10 R'. In the example shown, when the circuit is closed in the indicating circuit R the lamp R₂ is illuminated. However, of course, it will be understood that any form of visual

15 indicator may be used for giving notice to the user of the box that the refrigerating circuit is open or broken and that the defrosting period is on or off.

Referring to the means for adjusting the position of the circuit controller A, namely 20 the unit E, it will be observed that the same includes a manually adjustable screw 27 having a finger nob 28 and operating through a suitable bracket 29 supported on a wall or other part independent of the base D which 25 carries the electro-magnet and other parts. This screw may be provided with an indicating wheel 30 which may be calibrated to indicate the relative adjustment or location of the circuit controller A and is adapted to be 30 held in a set position by a pawl or equivalent element 31. The adjustable end of the screw 27 is preferably provided with a collar 32 for receiving the end of a bracket arm 33 carried by the base D while the tip end of the screw 34 is adapted to bear against the extension 35 of the arm B. The purpose of this arrangement is to move the circuit controller A closer to or farther away from the cooling unit U and at the same time maintain the 35 proper relative position between the head 17 of the armature and the dogs O and O' by moving the base on which the armature is mounted to the same degree that the arm is moved in one direction or the other. Thus, 40 the dogs O and O' will always be in position to alternately clear the movement of the armature element N since the original adjustment between the arm and the armature element N is maintained.

50 One of the advantages of the means described for operating the actuator F, namely the dogs O and O' is that if the magnet M should be energized unnecessarily or unexpectedly for any reason after the dog has been engaged, further movement thereof will not affect the other dog which must be engaged to throw the actuator to the opposite position. Thus, if an untimed impulse 55 should occur in the line which would tend to actuate the magnet M again the undesired reciprocation of the armature N will not affect the dog which is thrown out of position so that it cannot be engaged by the magnet.

60 Another advantage of the present invention resides in the provision of means which

effects a material economy in current consumption. Current is only passing through the defrosting circuit for a very short period, that is, only when the arm 2 is in engagement with either of the contacts 5 or 6 and 70 immediately upon the breaking of the circuit from either of the contacts 5 or 6 by the terminal changing switch H the circuit is quickly broken so that at no time is there any danger of current from the main lines 75 passing through the defrosting circuit. This prevents heating of any of the units included in the defrosting circuit.

Figure 6 illustrates a modification of the invention shown in Figs. 1 to 5. In all essential particulars, however, the features shown in the figures referred to are the same. For example, the mechanical parts such as the circuit controller A, carrier arm B and actuator F are all mounted on the axis or shaft C, while the dogs O and O' are controlled by the armature element N and electro-magnet M in the same way that they are in the construction previously described. Also the same type of transformer 11 and rectifier 10 are used. However, the switch operating in conjunction with the circuit controller A and the means for adjusting or setting the position of the latter with reference to the ice forming surface are different from those previously described.

In the modified arrangement, the switch operating in connection with the device A is designated as H² and includes a pair of fixed terminal contacts 36 and 37 which may be relatively long arcuate members respectively mounted on the insulated blocks, if desired, which carry the terminals of the switches S and R'. These contacts are adapted to be engaged by the contact 38 carried by the shiftable actuator arm F to alternately throw the circuit from terminal S of the circuit controller A to the terminal or contact 6 of the latter. The fact that these contacts overlap is intentional since it insures the circuit being closed to the electromagnet M until the actuator arm is moved past center by the spring G. It is of no consequence that the live contact bridges both contacts 10 at the same time momentarily because the circuit to the receiving contact of this switch is broken or open at the terminal or contact in the circuit controller when the actuator is moving.

11 Referring to Fig. 6 it will be seen that the contact 38 on the actuator is connected by wire 9a with the rectifier 10. When the parts are in the position shown and the ice contacts with the circuit controller A, the circuit will be closed through the wire 12a to the electromagnet M, thence through the wire 13a to the arm 2 of the circuit controller from whence it passes through wire 5b to terminal 36 which is in engagement with the movable contact 38 that is connected to the rectifier 12.

by wire 9a. When the box warms up after the ice melts the circuit is again closed by arm 2 engaging contact 6 which is electrically connected by wire 6b with the switch terminal contact 37. The circuit is then closed through contact 38 and wire 9a to the rectifier by wire 9a.

Another feature of this arrangement is that the electromagnet M, armature N and the axis C on which the actuator F and arm B are mounted are all carried by an adjustable base D². This base is mounted for sliding rectilinear movement on a casing part D³, as distinguished from an arcuate or partly circumferential movement as in the case of the base or platform D in Figs. 1 and 2. The purpose of this adjustment is to move the circuit controller A to a greater or less distance from the ice forming part of the cooling coil. Referring more in detail to the means of adjustment referred to, it will be seen that the base or platform D² carries guide elements 39 which may be provided with slots to receive the shanks of guide studs mounted on the casing part D³, the said studs having clamping heads 40 thereon to engage the members 39 and hold the same in the desired set position.

For the purpose of accurately moving the base D² to effect the desired setting of the circuit controller A an adjusting device E² is utilized. This device includes a bracket 41 or its equivalent carried by the base and engaged by an adjusting screw 42 having thereon a collar 43 which rides in a guiding element 44 carried by the casing part D³. By turning the screw 42 through the medium of the finger knob 45 the base D may be moved to any extent desired, and in that connection, the dial 46 carried by the shank of the screw may be placed in a more readily accessible and readable position so that the user of the box can conveniently move the entire defrosting unit to readily regulate the position of the circuit controller to adjust the defrosting cycle.

In this arrangement the extension 35a on the arm B is stopped at its extreme limits of movement by engaging with the abutments 36b.

In both forms of the invention the circuit controller A is preferably mounted on a self adjusting carrier or support so that it will not only follow uneven ice formation but will also permit sufficient range of movement for the arm B to assure efficient functioning of the parts actuating the arm.

As will be observed from Fig. 7 the circuit controller A has its casing 1 fitted with a tube 47 which enters a conical hood 48 carried by the arm B. This tube is engaged by a compressible conical spring 49 which abuts against the collar 50 and which is also anchored as at 51 to the arm B. This construction permits the circuit controller to have

both a universal compensating movement for uneven ice engagement and also permits the arm B to make its full forward stroke or movement by compressing the spring 49, thus always tending to force the circuit controller 70 against the ice formation and insuring it reaching the ice forming part when all the ice has melted.

The switch S in the main current supply line to the refrigerating apparatus is used 75 in addition to the usual thermostat switch which is operated by box temperatures to control the refrigerating cycle under normal conditions, and because the so-called defrosting circuit is connected with the source of 80 current supply ahead of the switch S, this circuit will operate independently of the thermostat control now commonly used on automatic refrigerators.

In connection with the operation of the 85 apparatus disclosed in Figs. 1, 2, and 3, it may be pointed out that with the range of adjustment afforded by the device E, the apparatus functions as a full automatic defrosting means according to the setting of the controller A with reference to the fins, baffles, or other ice collecting surface of the evaporator. That is to say, when the circuit controller A is adjusted or set a spaced distance 90 from the ice collecting surface, said circuit controller will not operate until the ice builds out to it or is in actuating proximity to it. However, by manually adjusting the device E to take up any space between an initially 95 distant setting from the ice forming surface 100 and the formation of the ice as it may exist, the circuit controller may be manually brought into operation. Therefore, the present construction is capable of functioning both as a full automatic and a semi-automatic apparatus in the sense that it can be 105 manually manipulated to start the defrosting period whenever desired.

Furthermore, it will be apparent that the 110 present mechanism includes a plurality of motor control switches, namely, the switch including the actuator F which cooperates with the motor control terminals S (Fig. 1 or its equivalent) and the thermal cutout or circuit controller A. Also an adjustment control means is provided for the switch mechanism. That is to say, the entire position of the switch F-S may be adjusted through the medium of the parts 32-33 and the parts 27 and 29. The adjustment of the 115 switch F-S and its associated parts also changes the effective position of the thermal cutout A with reference to the evaporator. The entire adjustment control mechanism or means consisting of the parts 27-29-30-33 120 and the arm 35 is in turn controlled by the unit control knob 28. By turning the knob 28 to its extreme movement in one direction the thermal cutout can be brought into contact with a part of the evaporator. By mov- 130

ing the unit control knob 28 in the opposite direction the thermal cutout can be moved to its maximum position away from the evaporator. Intermediate positions of the unit control knob 28 are effective to place the thermal cutout A at any desired location with reference to the evaporator. By means of the unit control knob 28 it will also be apparent that if the thermal cutout is spaced 10 away from the evaporator, that is in an inoperative position with reference to the ice formation, it can be moved to an operative position by simply turning the unit control knob to bring the thermal cutout into contact 15 with the ice formation. The reverse of this is also true.

Without further description it is thought that the features and advantages of the invention will be readily apparent to those 20 skilled in the art, and it will of course be understood that changes in the form, proportion and minor details of construction may be resorted to, without departing from the spirit 25 of the invention and scope of the appended claims.

I claim:

1. In a refrigerator, the combination with 30 the cooling unit and means for interrupting and restoring the refrigerating cycle there- to, of means adapted to contact with and follow the ice formation on the surface of the cooling unit to automatically control said means for interrupting and restoring the refrigerating cycle.

35 2. In a refrigerator, the combination with the cooling unit and an element for interrupting and restoring the refrigerating cycle, of means for automatically controlling said element including a device responsive to 40 changing temperature conditions, and means controlled by said device for causing the same to follow the ice formation on the cooling unit during melting and to reset the same after melting.

45 3. In a refrigerator, the combination with the cooling unit and an element for interrupting and restoring the refrigerating cycle, of means for automatically controlling said element including a device responsive to 50 changing temperature conditions, and means including a spring tensioned member carrying said device for causing the same to follow the ice formation on the cooling unit during melting and to reset the same after melting.

55 4. In a refrigerator, the combination with the cooling unit and an element for interrupting and restoring the refrigerating cycle, of means for automatically controlling said element including a device controlled by the 60 formation and melting of ice on the cooling unit and responsive to changing temperature conditions and means including a pivoted arm on which said device is mounted, an actuator member, a switch in circuit with said 65 device responsive to changing temperature

conditions, a spring operatively connecting the actuating member and switch, and means controlled by said device for operating the actuator member.

5. In a refrigerator, the combination with 70 an element for interrupting and restoring the refrigerating cycle, of means for automatically controlling said element including a device responsive to changing temperature conditions and including a shiftable conductor arm and spaced contacts, a circuit controlled by said device and including the said conductor arm and spaced contacts, a switch in said circuit, an electromagnet in said circuit, and means controlled by said electromagnet for operating said switch. 75

6. In a refrigerator, the combination with 80 an element for interrupting and restoring the refrigerating cycle, of means for automatically controlling said element including a device responsive to changing temperature conditions and including a thermostat controlled conductor arm and spaced adjustable contacts, a circuit controlled by said device and including the said conductor arm and spaced contacts, a switch in said circuit, an electromagnet in said circuit, and means controlled by said electromagnet for operating said switch. 85

7. In a refrigerator, the combination with 90 an element for interrupting and restoring the refrigerating cycle, of means for automatically controlling said element including a device responsive to changing temperature conditions, a pivoted arm on which said device is mounted, an actuator member mounted coaxially with the arm, a switch, a spring operatively connecting the actuator member and the arm, an armature, a spring for moving the armature in one direction, an electromagnet for moving the armature in the other direction, and means operated by said armature element for moving the actuator member. 100

8. In a refrigerator, the combination with 110 an element for interrupting and restoring the refrigerating cycle, of means for automatically controlling said element including a device responsive to changing temperature conditions, a pivoted arm on which said device is mounted, an actuator member mounted coaxially with the arm, a switch, a spring operatively connecting the actuator member and the arm, an armature, a spring for moving the armature in one direction, an electromagnet for moving the armature in the other direction, and a pair of reciprocating dog members carried by said arm and having offset portions thereon adapted to be engaged by the armature element in its movement, said dogs being spaced on opposite sides of the axis of the arm whereby they will be alternately thrown into and clear of the path of movement of said armature element. 115

9. In an electrical refrigerator a switch for 120 making and breaking the circuit to the re- 130

- frigerating apparatus, a cooling unit, and means for automatically defrosting the cooling unit and comprising means for operating said switch, said means including a defrosting circuit, a circuit controller operated by the formation and melting of ice on the cooling unit included in said defrosting circuit, a switch also included in the defrosting circuit, and means operated by closing said defrosting circuit to alternately operate the switch for making and breaking the circuit to the refrigerating apparatus.
10. In a refrigerator, a master switch for opening and closing the circuit to the refrigerating apparatus, a defrosting device including a circuit controller adapted to be actuated by ice and box temperature, an electromagnet, a terminal changing switch, a defrosting circuit having the terminal changing switch included therein, and actuating means operated by the electromagnet for shifting the terminal changing switch.
11. In an electrical refrigerator, the combination with the current supply line to the refrigerating apparatus and a cooling unit, of means controlled by the formation and melting of ice on the cooling unit for opening and closing the circuit in said current supply line.
12. In an electrical refrigerator, the combination with the current supply line to the refrigerating apparatus and a cooling unit, of switch means in said supply line, and means operated by the formation and melting of ice on the cooling unit for controlling the said switch means.
13. In an electrical refrigerator, the combination with the current supply line to the refrigerating apparatus and a cooling unit, of means controlled by the formation and melting of ice on the cooling unit for opening and closing the circuit in said current supply line, and means for indicating the defrosting period.
14. In an electrical refrigerator, the combination with the current supply line to the refrigerating apparatus and a cooling unit, of means controlled by the formation and melting of ice on the cooling unit for opening and closing the circuit in said current supply line, and means for visually indicating the duration of the defrosting period.
15. In an electrical refrigerator, the combination with a source of alternating current supply for the refrigerating apparatus, a switch for opening and closing the circuit to said refrigerating apparatus, a cooling unit, and a defrosting device including a defrosting circuit, means connected with the source of alternating current supply to furnish direct current to the defrosting circuit, a circuit controller included in said defrosting circuit and adapted to follow the ice formation on the cooling unit, and means operated by the circuit controller for temporarily closing the defrosting circuit.
16. In a refrigerator, the combination with means for interrupting and restoring the refrigerating cycle and the cooling unit, of means adapted to contact with and follow the ice formation on the cooling unit to automatically control said means for interrupting and restoring the refrigerating cycle, and means for spacing the means adapted to contact with and follow the ice formation at a greater and less distance from the said ice formation.
17. In a refrigerator, the combination with an element for interrupting and restoring the refrigerating cycle and a cooling unit, of means for automatically controlling said element including a device responsive to changing temperature conditions, means controlled by said device for causing the same to follow the ice formation on the cooling unit during melting and to reset the same after melting, and means for mounting said device whereby it may have a universal rocking and sliding movement independently of said means for causing the same to follow the ice formation.
18. In a refrigerator, the combination with an element for interrupting and restoring the refrigerating cycle and a cooling unit, of means for automatically controlling said element including a device responsive to changing temperature conditions, means controlled by said device for causing the same to follow the ice formation on the cooling unit during melting and to reset the same after melting, means for manually setting said device to vary the defrosting cycle, and means for mounting said device whereby it may have a universal rocking and sliding movement independently of said means for causing the same to follow the ice formation and rendering said means for manually setting the device effective under all conditions of use.
19. In a refrigerating system, the combination with the cooling unit, means for circulating a refrigerant medium through said unit and temperature responsive means for said first named means to maintain the unit between predetermined limits of temperature, of means for automatically opening and closing the circuit to said means for maintaining said unit between predetermined limits of temperature according to the degree of frost formation on the cooling unit and temperature conditions within the refrigerator.
20. In a refrigerating system, the combination with a cooling unit and an element comprising means for circulating a refrigerant medium through said unit and temperature responsive means for controlling said first mentioned means to maintain said unit between predetermined limits of temperature, of means for automatically controlling said element including a device responsive to the

- differential between ice and box temperature, a circuit controlled by said device, an electro-magnet, an armature operated by said electro-magnet and the latter being included in 5 said circuit, and means controlled by said armature for automatically making and breaking the circuit controlled by said device.
21. In an electrical refrigerator, the combination with the current supply line to the 10 refrigerating apparatus including means for circulating a refrigerant medium through an evaporator and temperature responsive means for controlling said first mentioned means to maintain the evaporator between 15 predetermined limits of temperature, of defrosting means arranged in the current supply line anterior to said refrigerating apparatus and controlled by the formation and melting of ice on the evaporator for opening 20 and closing the circuit in said supply line.
22. In an electrical refrigerator, the combination with the refrigerating apparatus including a motor operating switch and an evaporator, and the current supply line to the 25 motor and switch, of a defrosting switch device for opening and closing the circuit in said current supply line, and a thermostat device included in circuit with said defrosting switch and located at the evaporator, 30 and means for manually causing the operation of said thermostat.
23. Means for automatically defrosting the refrigerating unit of refrigerators equipped with electrically operated means 35 for circulating a refrigerant in the unit and means for maintaining said unit within predetermined temperature limits, comprising the combination with the current supply line to said electrically operated means, of means controlled by the formation and melting of 40 ice on said unit for opening and closing the circuit of the current supply line and means for regulating the frequency of defrosting periods.
- 45 24. Means for automatically defrosting the refrigerating unit of refrigerators equipped with electrically operated means for circulating a refrigerant in the unit and means for maintaining said unit within predetermined 50 temperature limits, comprising the combination with the current supply line to said electrically operated means, of means controlled by the formation and melting of ice on said unit for opening and closing the circuit of the 55 current supply line, and means for manually setting said last named means to regulate the frequency of defrosting periods.
25. Defrosting means for electrically operated refrigerators comprising the combination 60 with the refrigerating apparatus operating within predetermined temperature limits and the current supply line leading thereto, of a main switch for opening and closing the circuit in said current supply line, a circuit controller adapted to be actuated by low and 65 high temperature in the refrigerator, electro-magnetic means included in circuit with said circuit controller, a terminal changing switch also included in circuit with the electro-magnetic means, and means actuated by the said electro-magnetic means for shifting the said main and terminal changing switches. 70
26. Defrosting means for electrically operated refrigerators, comprising the combination with the refrigerating apparatus operating within predetermined temperature limits and the current supply line leading thereto, of electro-magnetically operated switch means in said current supply line anterior to the refrigerating apparatus, and a thermostat switch responsive to temperature changes in the refrigerator and included in circuit with the electro-magnetically operated switch means thereby to actuate the same and control the circuit in said supply line. 75
27. Defrosting means for electrically operated refrigerators, comprising the combination with the refrigerating apparatus operating within predetermined temperature limits and the current supply line leading thereto, of electro-magnetically operated switch means in said current supply line, and thermal responsive switch means in circuit with said electro-magnetically operated switch means actuated by the change in temperature occurring at the beginning and end of the defrosting period to control said electro-magnetically operated switch means to open and close the circuit in said current supply line. 80
28. A method of automatically defrosting refrigerating units of electrical ice boxes which consists in subjecting a thermal responsive element to the influence of direct contact with the ice formation on the refrigerating unit and causing said element to open the circuit to the motor of the refrigerating apparatus and simultaneously close a circuit to an indicating device, or vice versa. 85
29. Means for automatically defrosting the refrigerating unit of refrigerators equipped with electrically operated means for circulating a refrigerant in the unit, and means for maintaining said unit within predetermined temperature limits; comprising the combination with the current supply line to said electrically operated means, of a thermal-controlled electro-magnetic switch device included in the said current supply line 90 for opening the circuit therein. 110
30. Means for automatically defrosting the refrigerating unit of refrigerators equipped with electrically operated means for circulating a refrigerant in the unit, and means for maintaining said unit within predetermined temperature limits; comprising the combination with the current supply line to said electrically operated means, of a thermal-controlled electro-magnetic switch de- 115
- 120
- 125
- 130

- vice included in the said current supply line for closing the circuit therein.
31. Means for automatically defrosting the refrigerating unit of refrigerators equipped with electrically operated means for circulating a refrigerant in the unit and means for maintaining said unit within predetermined temperature limits; comprising the combination with the current supply line to 5 said electrically operated means, of a switch device located in said current supply line anterior to the refrigerating apparatus, and thermal-responsive means for operating the switch to control the circuit.
32. In an electrical refrigerator having an evaporator element, a switch in the current supply line to the mechanism for circulating refrigerant through the evaporator and temperature responsive means positioned to be 10 contacted by the ice formation on the evaporator element and operating to open said switch.
33. In an electrical refrigerator having an evaporator element, a switch in the current supply line to the mechanism for circulating refrigerant through the evaporator and temperature responsive devices for opening said 15 switch and for closing the same, one of said devices being positioned so as to be contacted by the ice formation on the evaporator to cause opening of the switch.
34. In an electrical refrigerator having an evaporator element, a switch in the current supply line to the mechanism for circulating refrigerant through the evaporator, temperature responsive means positioned to be 20 contacted by the ice formation on the evaporator element and operating to open said switch, and means for adjusting the temperature responsive means relative to the evaporator element.
35. In an electrical refrigerator, an evaporator, a switch in the current supply line, means controlled by the ice formation on the 25 exterior of the evaporator for controlling the operation of said switch, and means for adjusting the last named means relative to the evaporator.
36. In an electrical refrigerator, an evaporator, an electro-magnetic switch in the current supply line, means controlled by the formation of ice on the exterior of the evaporator for controlling the operation of said switch, and means for adjusting the last 30 named means relative to the evaporator.
37. In a refrigerator having an evaporator, means for temporarily suspending the refrigerating cycle of the evaporator to render the same capable of defrosting, means controlled by the formation and melting of ice on the evaporator for controlling said first 35 named means, and means for adjusting the said means controlled by the formation and melting of ice on the evaporator with reference to said evaporator.
38. In a refrigerator having an evaporator, means for temporarily suspending the refrigerating cycle of the evaporator to render the same capable of defrosting, and a movably supported member carrying therewith 40 means for controlling said first named means.
39. In an electrical refrigerator having an evaporator element, means for circulating a refrigerant medium through the evaporator including a motor, a plurality of motor control switches, an adjustment control for one of said switches, and a unit control comprising means for actuating the adjustment control to change the effective position of the latter, said means including a rotatable part 45 operatively associated with the last mentioned switch.
40. In an electrical refrigerator, an evaporator, means for circulating a refrigerant medium through the evaporator including a motor, means for controlling the motor comprising a switch mechanism, a thermal cutout mechanism, adjustment control means for the switch mechanism, and a unit control 50 comprising a handle for operating the adjustment control means.
41. In an electrical refrigerator, an evaporator, means for circulating a refrigerant medium through the evaporator including a motor, means for controlling the motor comprising a switch mechanism, a thermal cutout mechanism, adjustment control means for the switch mechanism, and a unit control 55 comprising a knob for operating the adjustment control means, said unit control also being adapted to render the thermal cutout mechanism effective and ineffective, respectively, the intermediate positions of the knob being effective to change the position of the adjustment control means as desired.
42. In an electrical refrigerator, an evaporator, means for circulating a refrigerant medium through the evaporator including a motor, means for controlling the motor comprising a switch mechanism, a thermal cutout mechanism, adjustment control means for the switch mechanism, and a unit control 60 comprising means for operating the adjustment control, said means being operatively associated with the thermal cutout mechanism for rendering the thermal cutout mechanism operative in one position of the adjustment control means and inoperative in another position thereof.
43. In an electrical refrigerator, an evaporator, means for circulating a refrigerant medium through the evaporator including a motor, means for controlling the motor comprising a switch mechanism, a thermal cutout mechanism, and a unit control comprising means for actuating the adjustment control, said means being operatively associated with the thermal cutout to render the same effective from an ineffective position.

44. In an electrical refrigerator, an evaporator, means for circulating a refrigerant medium through the evaporator including a motor, means for controlling the motor comprising a switch mechanism, a thermal cutout mechanism, an adjustment control means for the switch mechanism, and a unit control comprising a knob for actuating the adjustment control means, said knob being operatively associated with said thermal cutout to render the same operative and inoperative in different positions of the knob. 70
45. In an electrical refrigerator, an evaporator, means for circulating a refrigerant medium through the evaporator including a motor, means for controlling the motor comprising a switch mechanism, a thermal cutout mechanism, an adjustment control means for the switch mechanism, and a unit control comprising a control handle for adjusting the setting of the control switch and for rendering the thermal cutout mechanism inoperative and ready for operation in one position of the control handle. 75
46. Means for causing defrosting of a cooling unit in power refrigerating apparatus, including; a control member adjacent the cooling unit, said member adapted to be engaged by the coating of ice on the cooling unit, when said coating reaches a predetermined thickness, and means operated on contact of the ice coating with the controlling member for shutting off the power to the refrigerating apparatus. 80
47. A refrigerating system comprising means for starting and stopping a refrigerator at definite temperature limits successively for a plurality of cycles, and an automatic means for increasing the starting temperature to a defrosting temperature for a defrosting cycle after the said plurality of cycles. 85
48. A refrigerating system, comprising in combination a cooling element normally maintained at desired refrigerating temperatures, and means rendered operable automatically at intervals by the normal operation of the system to permit rise of the temperature of the cooling element to a defrosting temperature limit. 90
49. The method of automatically controlling frost formation on cooling units of refrigerators, which consists in maintaining a normal refrigerating cycle within predetermined limits to provide frost producing temperatures, and then automatically modifying the refrigerating cycle to produce frost melting temperatures. 95
50. The method of automatically controlling frost formation on cooling units of refrigerators, which consists in maintaining a normal refrigerating cycle within predetermined limits to provide frost producing temperatures, then automatically modifying the refrigerating cycle to produce frost melting temperatures, and subsequently automatically restoring the normal refrigerating cycle. 100
51. In an electrical refrigerator, including an evaporator, a switch in the current supply line, and means controlled by the ice formation on the exterior of the evaporator for controlling the operation of said switch. 105
52. In an electrical refrigerator including an evaporator, an electro-magnetic switch in the current supply line, and means controlled by the ice formation on the exterior of the evaporator for controlling the operation of said switch. 110
53. In a refrigerator having an evaporator, means for temporarily suspending the refrigerating cycle of the evaporator to render the same capable of defrosting, and means controlled by the formation and melting of ice on the evaporator for controlling the said first named means. 115
54. In a mechanical refrigerator, means for defrosting the evaporator thereof automatically comprising means for temporarily suspending the refrigerating cycle to render the evaporator capable of defrosting, and means operable when temperature conditions are such that the evaporator is cleared of ice for automatically restoring the refrigerating cycle upon completion of defrosting. 120
55. In a mechanical refrigerator, means for defrosting the evaporator thereof comprising means in the current supply line for opening the same temporarily to render the evaporator capable of defrosting, and means associated with the evaporator for controlling said first named means to restore the circuit in the current supply line and also restore the refrigerating cycle. 125
56. In a mechanical refrigerator including an evaporator, means actuated by the formation and melting of ice on the evaporator for automatically suspending temporarily the refrigerating cycle to render the evaporator thereof capable of defrosting, and means for indicating the duration of the defrosting period. 130

In testimony whereof I affix my signature.

CHARLES THOMAS HOFFMAN.

DISCLAIMER

1,916,315.—Charles Thomas Hoffman, Washington, D. C. MEANS FOR AUTOMATICALLY DEFROSTING REFRIGERATING UNITS. Patent dated July 4, 1933.
Disclaimer filed May 8, 1936, by the assignee, Lloyd M. Keighley.

Hereby enters this disclaimer to claims 47, 48, 49, and 50 of the specification.
